UNITED STATES PATENT OFFICE.

GEORGE BREED, OF PHILADELPHIA, PENNSYLVANIA, ASSIGNOR TO LYRACHORD COMPANY, OF NEW YORK, N. Y., A CORPORATION OF NEW YORK.

ELECTROMAGNETIC MUSICAL INSTRUMENT.

1,233,306.

Specification of Letters Patent. Patented July 17, 1917.

Application filed February 6, 1915. Serial No. 6,452.

To all whom it may concern:

Be it known that I, GEORGE BREED, a citizen of the United States, residing in the city of Philadelphia, county of Philadelphia, 5 and State of Pennsylvania, have invented certain Improvements in Electromagnetic Musical Instruments, of which the following is a specification.

My improvements are designed primarily 10 to simplify the construction, eliminate eccentricities of action, secure better phase relations and prevent interferences with the desired vibrations of the musical strings, with the production of improved musical 15 effects, particularly in electro-magnetic pianos, a leading purpose being to provide improved means for connecting piano strings with the means for pulsating the current passing through the electro-magnets 20 and thereby effecting the desired pulsations.

A further purpose of my improvements is to obtain a more substantial and convenient construction, adapted to be adjusted to modify the tones of the instrument.

25 The characteristic features of the invention are fully disclosed in the following description and the accompanying drawings in illustration thereof.

In the drawings, Figure 1 is a broken 30 sectional and diagrammatic view of parts of a piano having a form of my improvements applied thereto; Fig. 2 is a broken front elevation of part of the construction shown in Fig. 1; Fig. 3 is a broken perspective view 35 of an element illustrated in elevation in Fig. 2; Fig. 4 is a sectional side view of a construction similar to that shown in perspective in Fig. 3, with a modified contact holder; Fig. 5 is a sectional side elevation 40 illustrating modified details of construction; Fig. 6 is a broken front elevation of details of construction shown in Fig. 5; and Fig. 7 is a broken sectional view taken on the line 45 $x-x$ of Fig. 5.

The instrument, as illustrated in Figs. 1 to 4 inclusive, comprises the usual plate 1 provided with the V-bar or bridge 2, the bridge 3 and the pins 4, and the sounding board 6 provided with the bridge 7, which 50 hold the strings 8, the latter being engaged between the bridges 2 and 3 by the pressure bar 9.

In the form of the invention here illustrated, the bearings 10 of insulating material 55 are fixed on the pressure bar 9 and insulat-

ing brackets 11 are connected to these bearings by screws 12. The bearings 10 have the conducting clips 13 fixed thereon and the brackets 11 have fixed thereto the conducting clips 14 engaging the clips 13, the clips 14 having the resilient blades 14' adapted to be adjusted in the recesses 11' of the brackets by set screws 15. The springs 14' are connected by fine wires 16 with the wire arms or hangers 17 provided with the coils 17' by which they are fulcrumed on pintles 18 and with the coils 17'' in which are screwed the carbon contacts 19. Wire hangers 20 are gripped in clamps 21 fixed on the bearings 10 and are provided with eyes 20' for adjustment and coils 21'' for holding the carbon contacts 22 which co-operate with the contacts 19. The wires 20 are adapted to be turned in the clamps 21 for the purpose of changing the relation between the carbon contacts 19 and 22, the adjustment thus effected modifying the pulsations of current passing through such contacts. Silk phase strings 23 connect musical strings 8 with the pulsator comprising the contacts 19 and 22, the connection being made in various ways, as by drawing the string 23 from a string 8 across the coil 21'' and around the wire 20 to an anchorage 24 in the member 10; or carrying such string 23 along and against the coils to an anchorage 24 in a block 11, the tension of the strings being variable by turning the members 20. The several arrangements are commonly found in a single instrument. A particular arrangement is 90 not essential and the arrangements are varied by trial so as to produce the desired musical effect.

Each pulsator has its contacts 19 and 22 connected in circuit with an electro-magnet 25 (through the field of which passes a string 8) and a source of electric energy 26, the circuit comprising a conductor 27 connecting the electro-magnet 25 with the battery 26, a conductor 28 connecting the battery 26 with the conductor 20 through the clips 21, a conductor 29 connecting the clips 13 with the resilient contact 30, and a conductor 31 connecting the electro-magnet 25 with the resilient contact 32, the contacts 30 and 32 being electrically separated normally by the supporting member 33 carried by the bar 34. An abstract 35, adapted to be elevated by the key or lever 36, carries an adjustable member 38 for lifting the resilient 110

contact 32 into engagement with the like contact 30.

In operation, upon closing a circuit containing an electro-magnet and a pulsator, 5 the corresponding piano string is vibrated by the actions of the electro-magnet and the pulsator, the corresponding spring 14' acting through the connected fine wire 16 upon the arm 17 to hold the contact 19 against 10 the contact 22 and the pressure between the contacts being regulated through the regulation of the tension of the fine wire by the current. When the musical effect is not satisfactory, it can be corrected by trial 15 through turning the device 20 corresponding to the string 8 producing the note, so as to change the contacting relation between the parts 19 and 22, and also the tension of the string 23 which coordinates the actions 20 of the musical string and the current.

I have found that most satisfactory results are obtained by attaching the phase strings 23 to the strings 8 near or in contact with one of the bridges, the strings 23 25 having the function of effecting the desired phase relation between the sonorous members and pulsators and being adjustable by varying their relation to the pulsators and sonorous members.

30 In the form of the invention illustrated in Figs. 5 to 7 inclusive, the strings 8, supported by the plate 1 through the parts 2, 3, 4, and 7 (see Fig. 1) are connected with coils 21' (on hangers 20 for holding contacts 22) by extensions 21^a abutting against the strings, or extensions 21^c in frictional contact with the strings, or a brush like construction 21^d having fibers between which the strings are drawn, the parts 21^a, 21^b, 21^c, and 21^d being adapted for mechanically coördinating the vibrations of the musical strings and the pulsations of the current pulsating mechanism.

Having described my invention, I claim: 45 1. In a musical instrument, the combination of musical strings, circuits containing electro-magnets for actuating said strings and current pulsating devices, and flexible strings connected with said musical strings 50 and engaging said pulsators, said flexible strings drawn between an anchorage and said musical strings in contact with said pulsators.

55 2. In a musical instrument, the combination of a musical string, a circuit containing an electro-magnet for actuating said string and a current pulsating mechanism comprising resilient supporting devices ear-

rying contacts, and a flexible string drawn from said musical string across said mechanism in contact therewith. 60

3. In a musical instrument, the combination of a musical string, a circuit containing means for actuating said string and current pulsating mechanism comprising contacts, 65 and a journaled device carrying one of said contacts for setting the relation of said contacts.

4. In a musical instrument, the combination with a musical string, of a circuit containing an electro-magnet adapted for actuating said string and current pulsating mechanism comprising a pair of hangers in said circuit, contacts carried by said hangers, means whereby the engagement between 75 said contacts can be varied, and means for directly connecting said pulsator with said musical string, said means comprising a string drawn across and engaging a part of said pulsator. 80

5. In a musical instrument, the combination with a musical string, of a circuit containing an electro-magnet and a current pulsator comprising a journaled conducting device, a contact carried by said device, a 85 second conducting device, and a contact carried by said second conducting device in engagement with said contact first named.

6. In a musical instrument, a musical string, a circuit containing an electro-magnet and a pulsator comprising a conductor in said circuit, a contact carried by said conductor, a second conductor in said circuit, a contact carried by said second conductor in engagement with said contact 95 first named, a fine wire in said circuit in engagement with said second conductor, and a tension member connected with said fine wire in said circuit, in combination with means connecting said pulsator directly 100 with said musical string so as to mechanically coördinate the vibrations of said musical string and the action of said pulsator.

7. In a musical instrument, the combination with a musical string, of a circuit containing an electro-magnet and a pulsator comprising contacts, and means for turning 105 one of said contacts.

In testimony whereof I have hereunto set my name this 27th day of January, 1915, 110 in the presence of the subscribing witnesses.

GEORGE BREED.
